CLAIM

The ornamental design for a storage device for boxed and bottled goods, as shown and described.

DESCRIPTION

FIG. 1 is a perspective view of a storage device for boxed and bottled goods;

FIG. 2 is a front view of the storage device;

FIG. 3 is a side view of the storage device;

FIG. 4 is a top view of the storage device; and,

FIG. 5 is a bottom view of the storage device.

The broken lines in FIG. 5 depict portions of the storage device that form no part of the claimed design.
